DRY DOCK

Original Filed Oct. 16, 1919

UNITED STATES PATENT OFFICE.

DAVID E. WILLIAMS, OF CLEVELAND, OHIO, SARA E. WILLIAMS ADMINISTRATRIX
OF SAID DAVID E. WILLIAMS, DECEASED.

DRY DOCK.

Application filed October 16, 1919, Serial No. 330,972. Renewed July 21, 1924.

To all whom it may concern:

Be it known that I, DAVID E. WILLIAMS, a citizen of the United States, and a resident of Cleveland, county of Cuyahoga, and 5 State of Ohio, have invented a new and useful Improvement in Dry Docks, of which the following is a specification, the principle of the invention being herein explained and the best mode in which I have contemplated 10 applying that principle, so as to distinguish it from other inventions.

The present improvements, relating to dry docks, have more particular regard to a dry dock of the type described and broadly 15 claimed in my co-pending application filed May 7, 1919, Serial No. 295,722. Briefly stated, this dock consists of a structure of monolithic concrete in the form of an open normally buoyant rectangular vessel 20 having its one end removed and adapted to be closed by a gate, the floor of said vessel extending beyond the side walls thereof, and a back-fill resting on such projecting floor-portion and retaining the structure in 25 place below the water level at a depth adapting the same to receive vessels requiring to be docked. As described in said co-pending application, the vessel in question is constructed out of water, and is then launched 30 or set afloat in the water and floated under its own buoyancy to a previously prepared slip or basin; and after the dock has been properly positioned in such basin, with its outer end of course directed toward the 35 channel, it is sunk to the desired level and there maintained firmly in place by filling in earth around its side walls so as to cause same to rest on such projecting floor portion. It has been found, however, that in some cases 40 it may be desirable to locate the dock in effect in open water, instead of in a slip or basin cut to approximately the dimensions of such dock in plan. The object of the present modification in construction, accordingly, is to adapt the dock structure for 45 the retention of earth or equivalent ballast on such laterally extending floor portion, irrespective of whether there be a solid earth wall adjacent the side wall of the dock or 50 not.

To the accomplishment of the foregoing and related objects, the invention, then, consists of the means hereinafter fully described and particularly pointed out in the 55 claims, the annexed drawing and the follow-

ing description setting forth in detail certain mechanism embodying the invention, such disclosed means constituting, however, but one of various mechanical forms in which the principle of the invention may be used.

In said annexed drawing:—

Fig. 1 is a transverse sectional view of my present improved design of dock; and Fig. 2 is a broken plan view of the same. 65

The general features of construction of the present dock being the same as in the case of my previous design fully described in my aforesaid co-pending application, it is believed unnecessary to show a full plan 70 of the same or such details as the gate or caisson, which is used to close the open end of the dock. As already indicated, the dock is poured or molded in a suitable form or forms so as to be an integral monolithic 75 concrete vessel, of general rectangular form, with one end wall omitted so as to leave such end open. In order that the walls 1 may be made as thin as possible, such walls are suitably reinforced by means of metal re- 80 forcing rods or the like embedded therein, as need not be described in detail for the purpose in hand, and are then furthermore provided with integral buttresses 2, either within or without or both within and with- 85 out, placed at suitable intervals along the sides and the closed end of the structure. The floor 3 of the structure is constructed of relatively thin section, supported by a plurality of inverted transverse ribs or 90 girders 5, and by a plurality of longitudinal girders 4 spanning in such a fashion as to provide the same resistance to the forces of buoyancy as would be provided in the event 95 the floor was built of a solid mass of con- 100 crete or masonry of a thickness sufficient to overcome the hydrostatic head by dead weight. The transverse girders 5 preferably correspond in location with the aforesaid buttresses 2, the bases 5^a of such but- 105 tresses on the outside of the walls 1 constituting in effect merely continuations of the corresponding girders. It will be further noted that the floor extends beyond the walls on either side of the structure, it being upon 110 these laterally projecting floor portions 6, or rather upon such corresponding girder extensions 5^a, that the external buttresses proper have their base.

This present dock is constructed in such a 110

manner that one-half or more of the weight required to overcome buoyancy is composed of inexpensive material such as soil or sand as compared with solid masonry or concrete 5 as used in the usual manner of graving dock construction, thus permitting the use of small sections and the more economical arrangement of material. The forces acting on the bottom of the dock are collected by 10 the floor system and transmitted to the transverse girders, which in turn transmit such forces to the foundations or to the vertical abutments that coincide with such transverse girders; while conversely the forces acting 15 on the side walls of the dock are collected and transmitted to the vertical buttresses and in turn to such coinciding transverse girders.

It will furthermore be seen that the two sets of forces just referred to oppose each 20 other and, to the extent that they are equal, such forces will neutralize each other. In other words the two rows of piles or blocks upon which the dock is brought to rest with its respective side walls located thereover, 25 constitute in effect lines upon which the longitudinal halves of the dock may be regarded as being fulcrumed. The hydrostatic pressure acting on the bottom of the dock is converted into a turning effect that is resisted by the counterturning effect of the 30 pressure against the side walls, just as if such pressures were applied to the two arms of a bell crank.

The foregoing statement has regard more 35 especially to the situation where the dock is empty. When it is full, the hydrostatic pressure under the floor is of course more nearly balanced by the weight of the water within. In this condition, it is the pressure 40 against the side walls that requires to be resisted, but here the principle of construction just explained comes into play again, but in reverse fashion, i. e. the bottom system, by being tied to the side walls through the coincident transverse girders and buttresses resists the turning movement, just as before.

To meet the exigency of the situation above referred to, where no permanent earth wall is closely enough adjacent to the side 50 wall of the structure to retain in place the earth which is designed to be filled in and rest upon such projecting girder extensions and floor portions 6, I employ a supplemental or curtain wall 10 which rises integrally 55 from the outer edge of the floor portion 6 parallel with and to a height necessary to retain sufficient earth or a height sufficient to help support a pier, as will be presently explained. This wall 10 is formed of concrete 60 in the same fashion as such main wall 1, and is strengthened by vertical ribs 11 corresponding in position with the buttresses 2, and tied through the medium of transverse members 12 to such buttresses and thus to 65 the main wall, said structure acting as a unit

to resist overturning of walls. This outer wall 10 with its vertical ribs and transverse members 12 together with the buttress inner wall acts as a unit to transmit the turning forces in the same manner as the single outer wall in my copending application, Serial No. 295,722 in the manner previously described. There is thus provided a chamber or series of chambers between the two walls, similar to those provided at the forward end of the dock shown in my aforesaid application for the reception of pumping machinery and other operating equipment, with the difference that in the present case such chambers are designed for the reception and retention 70 of earth or equivalent ballast. 75

In other words, after the dock has been properly positioned over the site previously prepared for it, it is sunk to the desired level and there maintained permanently in place by filling earth into these chambers until the normal buoyancy of the structure is sufficiently overcome to bring the bottom of such structure to such desired level. Such level, as before, is desirably determined by the tops of piling 13 or equivalent means located under the respective side and end walls of the dock at suitable spaced intervals. Should it ever be desired to move or transfer the dock, this can be readily accomplished by simply removing the earth thus filled into the chambers between the aforesaid walls of the structure. 90

I also show in Fig. 1 a culvert 14 that extends longitudinally of the base of each main wall 1, such culvert being connected with the interior of the dock through the medium of ducts 15, so as to drain the latter to the pump chambers (shown in my copending application) when the dock is being emptied. I also show a platform or pier 16 as being supported above the walls 1 and 10 covering the chamber between the latter, into which the earth is filled as aforesaid to properly weight down the dock. 100

Other modes of applying the principle of my invention may be employed instead of the one explained, change being made as regards the mechanism herein disclosed, provided the means stated by any of the following claims or the equivalent of such stated means be employed. 105

I therefore particularly point out and distinctly claim as my invention:—

1. A dry-dock comprising a normally buoyant structure of monolithic concrete in the form of an open rectangular vessel, the floor of said vessel extending beyond the side walls thereof, a plurality of spaced buttresses rising from the floor of said vessel along the outside of the walls thereof, and a curtain wall on said projecting floor-portion, spaced from the adjacent side-wall but tied thereto through such outside buttresses so as to provide a chamber laterally adjacent to 115 120 125 130

- said dry-dock, such chamber being open above for the reception of earth or equivalent ballast, said spaced buttresses along said outside walls and curtain walls being 5 adapted to collect the forces acting on said walls and transmit the same to the bottom of said vessel.
2. A dry-dock comprising a normally buoyant structure of monolithic concrete in 10 the form of an open rectangular vessel, the floor of said vessel extending beyond the side walls thereof, a plurality of reinforcing ribs extending transversely of the floor of said vessel, a plurality of spaced buttresses rising from the floor of said vessel along both the inside and outside of the walls thereof, and a curtain wall on said projecting floor-portion, spaced from the adjacent side-wall but tied thereto through such 15 outside buttresses, so as to provide a chamber laterally adjacent to said dry-dock, such chamber being open above for the reception of earth or equivalent ballast, said ribs and buttresses on said outside and curtain walls 20 being adapted to collect the forces acting on the bottom of the vessel and on the walls respectively and to oppose the same each to the other.
3. A dry-dock comprising a normally buoyant structure of monolithic concrete in 25 the form of an open rectangular vessel, the floor of said vessel extending beyond the side walls thereof, a plurality of reinforcing ribs extending transversely of the floor of said vessel, a curtain wall on said projecting floor portion spaced from the adjacent side wall 30 so as to provide a chamber laterally adjacent to said drydock, such chamber being open above for the reception of ballast material, buttresses on the side walls and ribs on said curtain walls and extending into said buttresses on said side walls, and transverse members connecting said ribs and buttresses to tie said curtain and side wall together to 35 act as a unit, said buttresses and ribs being adapted to collect the forces acting on the bottom and walls of said dry-dock respectively and to oppose the same each to the other.
4. A dry-dock comprising a normally buoyant structure of monolithic concrete in the form of an open rectangular vessel, the 40 floor of said vessel extending beyond the side walls thereof, a plurality of reinforcing ribs extending transversely of the floor of said vessel, a curtain wall on said projecting floor portion spaced from the adjacent side wall 45 so as to provide a chamber laterally adjacent to said drydock, such chamber being open above for the reception of ballast material, buttresses on the side walls and ribs on said curtain walls and extending into said buttresses on said side walls, and transverse members connecting said ribs and buttresses to tie said curtain and side wall together to act as a unit, said buttresses and ribs being 50 adapted to collect the forces acting on the bottom and walls of said dry-dock respectively and to oppose the same each to the other.
5. A dry-dock comprising a normally buoyant structure of monolithic concrete in the form of an open rectangular vessel, the 55 floor of said vessel extending beyond the side walls thereof, a plurality of reinforcing ribs extending transversely of the floor of said vessel, a curtain wall on said projecting floor portion spaced from the adjacent side wall 60 so as to provide a chamber laterally adjacent to said drydock, such chamber being open above for the reception of ballast material, buttresses on the side walls and ribs on said curtain walls and extending into said buttresses on said side walls, and transverse members connecting said ribs and buttresses to tie said curtain and side wall together to act as a unit, said buttresses and ribs being 65 adapted to collect the forces acting on the bottom and walls of said dry-dock respectively and to oppose the same each to the other.

Signed by me, this 7th day of October, 1919.

DAVID E. WILLIAMS.
